(57) **CLAIM**

The ornamental design for input device with knob, as shown and described.

DESCRIPTION

FIG. 1 is a perspective view of input device with knob showing our new design;

FIG. 2 is a second perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view.

The broken lines shown in the figures form no part of the claimed design.
